UNITED STATES PATENT OFFICE.

HARRY LYON, OF BROCKTON, MASSACHUSETTS, ASSIGNOR TO JOHN A. BARBOUR AND PERLEY E. BARBOUR, BOTH OF BROCKTON, MASSACHUSETTS, DOING BUSINESS UNDER THE FIRM-NAME AND STYLE OF BROCKTON RAND COMPANY.

METHOD OF MAKING WELTS AND THE RESULTANT PRODUCT.

1,293,135.

Specification of Letters Patent.

Patented Feb. 4, 1919.

Application filed August 29, 1918. Serial No. 251,886.

To all whom it may concern:

Be it known that I, HARRY LYON, a citizen of the United States, residing at Brockton, in the county of Plymouth and State of Massachusetts, have invented new and useful Improvements in Methods of Making Welts and the Resultant Product, of which the following is a specification.

The present invention relates to welting for use in the manufacture of boots and shoes, and is concerned with a mode of producing two welts from a strip of leather, or of any other material which may be suitable for welting, by which economy of material is secured without sacrifice of strength or any other desirable quality of the finished welt. In other words the object of my invention is to produce welts equal to the best heretofore produced in a manner which 20 effects a saving of material.

The invention consists in the novel method of making welts, and in the product resulting therefrom hereinafter described and particularly pointed out in the appended claims. In the drawings forming a part of this specification,

Figure 1 is a plan view of part of a strip adapted to furnish two welts according to the present invention. Fig. 2 is an end view 30 of the strip. Fig. 3 is a plan view of one surface of the strip after the same has been grooved. Fig. 4 is an end view of the same strip after grooving, but on an enlarged scale, showing the location of the cut on 35 which the strip is divided to form two welts. Figs. 5 and 6 are similar views of the two welts after being separated from one another. Fig. 7 is a similar view of the welt shown in Fig. 6 after having been brought 40 to approximately the form which it possesses when it has been stitched to the upper and innersole in a shoe. Fig. 8 is a cross sectional view of a lasted shoe showing the innersole upper and welt connected together 45 by the inseam. Fig. 9 is an end view of a welt heretofore commonly used.

The same reference characters indicate the same parts in all the figures.

For economy of words it will be assumed 50 in the following description that the material operated upon according to my method to make welting is leather, wherefore it will generally be so described. This fact, how-

ever, is not intended as in any wise a limitation as to the material which might be used. 55 On the contrary the method and product which I desire to protect herein are independent of material, and may be respectively practised upon and made of any material whatever which is or may be suitable for 60 welts.

I first take a strip *a* of leather or other material which is much wider than a single welt, but is narrower than the sum of the widths of the two welts to be made therefrom. 65 In case the welts are to be provided with stitching grooves, I form two longitudinal grooves *b*, *c* in the flesh side of the strip on opposite sides of the longitudinal center line and equally distant from the opposite edges. 70 I then cut the strip lengthwise by an angular cut *d*, *d'*, which is V-shaped in cross section but extends substantially without deviation from one end of the strip to the other. The point or vertex *e* of the V-shaped cut is 75 approximately midway between the opposite faces of the strip, while the sides of the cut extend therefrom on opposite inclinations toward these faces. Preferably such sides make equal angles with the faces of 80 the strip, and preferably also such angles are approximately 45 degrees. When both welts are to have the same finished width, as is usually the case, the cut as a whole is located as nearly as possible midway between the opposite edges of the strip, the vertex *e* being then at one side of the vertical medial plane of the strip, the location of which is indicated by the dotted line *m*—*p* in Figs. 3 and 4, and both sides of the 85 cut crossing and being bisected by such medial plane. It will be understood of course that the straight lines represented *d* and *d'* in Fig. 4 indicate the planes which I have here called the sides of the cut. The point *e* 90 where these lines meet is the vertex of the cut. Both welts are symmetrical in the sense that (excluding the stitching grooves) the portions of each on opposite sides of the horizontal middle plane are alike. 95

In case the welts are not required to have a stitching groove, the step of grooving prior to cutting may be omitted, or in any case the grooving operation may be performed on the separate welts after they have been cut 100 and separated. The result of the operations 105

thus described is to produce two welts, *f* and *g* of which the former is V-shaped or has a V-shaped rib *h* at one edge, this being the edge which lies next to the inseam when the welt is applied to the shoe; and the other has a longitudinal V-shaped groove complementary to such rib at the corresponding edge. The lips *k* and *k'* bounding this groove are adapted to be brought together 10 into what is substantially a V-shaped rib similar to the rib *h* of the welt *f*, as shown in Fig. 7.

Said lips may be thus brought together and retained by adhesive, if desired, prior to 15 the application of the welt to a shoe, or they may be left separated. Even if left in this condition, the lips will be brought more or less closely together by the welt guide of the inseam stitcher when the welt is applied, 20 and in any event that lip which is placed next to the shoe upper in the application of the welt is bent so that the stitches of the inseam will be sure to lie in a part of the welt which has sufficient thickness and strength.

25 In other words the formation of the V-shaped groove in the inner edge of welt *g* does not diminish the thickness of the part of the welt in which the stitches are sewed, and therefore does not make it any less 30 strong than welts which are made without any such groove. Likewise the beveling of the welt *f* by the V-shaped cut does not weaken the latter, because as will be seen from Fig. 8, the stitches of the inseam pass 35 through that part of the welt which is not diminished in width by such beveling. Indeed the bevel formed by that side of the cut designated as *d'* is of advantage in that it enables the welt to fit snugly the outer lip 40 angle of the innersole, as is shown by Fig. 8; and the same effect occurs in the case of the welt *g* by reason of the groove in its edge which allows the lip *k'* to conform itself to the same angle. As a matter of fact the 45 welts heretofore used have been commonly beveled in substantially the manner shown at *l* in Fig. 9 (which represents a form of welt heretofore in wide use) for this very purpose.

50 The beneficial result accomplished by this invention is that each finished welt, while having the requisite total width, is more than half the width of the strip *a*, and the sum of the over-all widths of both strips is 55 greater than the total width of strip *a*. The amount by which such sum exceeds the width of the original strip is the measure of the saving of material accomplished by the invention; and while it is greater or less in absolute amount for welts of different thicknesses and widths, proportionally it is substantially the same in all cases.

In making the previously used welts

shown in Fig. 9, the welt is cut with a rectangular cross section, whereby the width of any strip from which such welts are made is equal to the sum of all the welts cut from it. Then one corner is cut off to form the bevel *l*, preparatory to use, and the part so cut off becomes waste. After the welt has 60 been stitched on and when the inseam is trimmed, the opposite corner *n* at the same edge is trimmed off more or less nearly to the dotted line shown in Fig. 9, and is wasted 70 also. Thus with my invention the wasted 75 corners of the old type of welt are in effect saved and made integral parts of the new welt, which latter may be made identical in dimensions, proportions, and shape with the old welt, and at the same time two of them 80 are produced from a strip which has less than enough material to make two welts by the old method.

What I claim and desire to secure by Letters Patent is:

1. The method of making welts which consists in providing a strip of material, and dividing the same lengthwise by a medial V-shaped cut, thereby producing two welts of which the width of each is more than half 90 the total width of said strip.

2. The method of making welts which consists in first providing a strip of material having a width less than the total width of two welts to be produced therefrom, and then dividing the strip into two parts by a longitudinal cut which is V-shaped in cross section, and of which the opposite sides make approximately equal angles with the opposite faces of the strip respectively.

3. The method of making welts which consists in dividing a strip of material into two parts on planes which extend at substantially equal angles and on respectively opposite inclinations from the opposite broad faces of 105 the strip and meet approximately midway between such faces, said planes extending also longitudinally of the strip.

4. The method of making welts which consists in providing a strip and dividing the 110 same longitudinally into two welts, each having a total width of more than half the width of the entire strip, by cutting the same with a V-shaped cut, the vertex of which is approximately midway between the broad faces 115 of the strip at one side of the longitudinal medial plane, and the sides of which extend on approximately equal angles to such faces and cross such medial plane.

5. A welt formed with a longitudinal V-shaped groove in one edge, the lips flanking such groove being similar to one another and bent together forming a double-beveled edge.

In testimony whereof I have affixed my signature.

HARRY LYON.
